ATTORNEY

UNITED STATES PATENT OFFICE.

WILLIAM C. HEINDL, OF ROCHESTER, NEW YORK.

DESIGN FOR A PINWHEEL.

60,094.

Specification for Design.

Patented Dec. 27, 1921.

Application filed December 8, 1919. Serial No. 343,432. Term of patent 3½ years.

To all whom it may concern:

Be it known that I, WILLIAM C. HEINDL, a citizen of the United States, residing at Rochester, in the county of Monroe and State of New York, have invented a new, original, and ornamental Design for Pinwheels, of which the following is a specification, reference being had to the accompanying drawing, forming part thereof.

Figure 1 is a front elevation of the pin wheel.

I claim:

The ornamental design for a pinwheel as shown.

In testimony whereof I affix my signature.

WILLIAM C. HEINDL.
